UNITED STATES PATENT OFFICE.

EDWARD E. HINRICHSEN, OF NEW YORK, N. Y., ASSIGNEE, BY MESNE ASSIGNMENTS,
TO WESTERN ELECTRIC COMPANY, INCORPORATED, A CORPORATION OF NEW
YORK.

TROUBLE-INDICATING SYSTEM.

Application filed April 15, 1925. Serial No. 23,235.

This invention relates to telephone exchange systems and more particularly it has to do with telephone systems of the class wherein automatic switching apparatus is employed either entirely, or in part, for the establishment of the conversational connections.

In telephone systems, where automatic or semi-automatic switching apparatus is employed for establishing conversational connections in response to predetermined impulses transmitted by a subscriber or an operator, it is found that the efficiency of operation of the system may be materially increased by providing a means by which the apparatus may be capable of registering two or more cases of trouble which may occur in completing connections.

In positions where recording senders are located at a central office for receiving records from calling subscribers' lines or from operators' positions to, in turn, exercise a control over the operation of a series of selective switches, it is found that the efficiency and speed of operation may be enhanced by providing a number of controlling mechanisms or markers also situated at the central office and separate from the recording senders. A part of the duties ordinarily performed by the senders are delegated to these markers which receive a portion of the record from the senders to which they are connected and thereupon govern the selective operation of one or more of the switches. Other markers may be subsequently associated with the senders and in their turn govern succeeding switches to further extend the connection. These markers being equivalent, are arranged so that any sender may select any one of the markers, according to their busy or idle condition at the time. The markers are also common to a number of selector switches at one or more switching stages and may be associated with any switch for the purpose of controlling the same.

It is during the period that a marker is attached to a sender and to a selective switch that a substantial portion of the operations, incident to the setting of the switch, takes place. In other words, the various sequential operations which go to make up the selecting, testing and seizing at the selective switch are accomplished

under the control of the marker and while it is attached. Due to the wide latitude which the marker has in its association with other pieces of apparatus, and owing to the comparatively large number of sequential operations which comprise the total function of the marker, it is particularly desirable in the event the marker encounters trouble, to ascertain the relation of the marker to the other apparatus and the point to which it has progressed at the time of the trouble.

Heretofore, the means for registering a case of trouble in the marker was such that if a second case occurred while the trouble indicating means was engaged, the second case would be held in the marker for such time as is prescribed for its registration, before the marker could be released, and if the indicating means in the meantime had not become idle, the second case of trouble would not be registered and the record thereof would be lost.

The object of the invention is therefore to obtain a complete record of all cases of trouble which occur in the markers during the establishment of telephonic connections and such records are designed to show the points in the selective apparatus to which the calls progress when the trouble occurred.

A feature of the invention relates to a plurality of trouble indicating devices common to a number of switch controlling markers which become associated in predetermined order with the markers, as they encounter trouble.

Another feature of the invention relates to the trouble indicating control device which is adapted to effect the selection of any one of the indicating devices and to cause the release of the marker when a case of trouble therein is registered.

A further feature relates to the use of a common recorder adapted to make a permanent record of all cases of trouble occurring in the markers.

This invention is in the nature of an improvement of the system shown and described in the copending application of E. B. Craft and L. Keller, Serial No. 747,174, filed November 1, 1924, and in Patent No. 1,594,003, issued July 27, 1926 to W. W. Carpenter, and a general reference is hereby made to said disclosures for an understand-

ing of the manner in which the various parts of the present system are arranged and the details of the operation wherever such arrangements and details are hereinafter mentioned, but not particularly illustrated or described.

For the purpose of this case, it has been considered sufficient to show only such part of the apparatus or mechanism as is necessary for a clear understanding of the present invention and to confine the detailed description of the apparatus involved to the controlling means for establishing the connections of the disabled markers to the indicating devices and the connections of the engaged indicating devices to the recorder.

The drawing, which is partly diagrammatical and partly in full detail, illustrates the trouble indicating control circuit and the means for associating it with the markers, trouble indicating devices and recorder.

General description of the system and apparatus.

25 Inasmuch as it is hardly probable that any more than two cases of trouble will occur about the same time unless some serious trouble in the system is encountered which would then require special handling, 30 it is believed that a description of the invention as a duplex arrangement of indicating devices operating alternately, will be the most practical for a general understanding of the utility of the invention.

35 Referring now for the moment to the drawing, description will be given of the general plan of the system. An idle marker of a group comprising those diagrammatically shown as 11 and 12 is selected to 40 govern the selective operation of one or more of the switches provided for completing a telephonic connection. If the marker is functioning normally the necessary time interval is allowed for the completion of the 45 connection and then the marker releases in the regular manner, but should any trouble be encountered a circuit would be closed in the marker to initiate the operation of the control, or connecting, circuit for the 50 purpose of connecting one of the two trouble indicating devices 51 and 52 (diagrammatically shown) to the particular marker which has encountered trouble. To this 55 end, two groups of multi-contact relays are provided in the control circuit and these groups are interconnected by a group of common leads such as 33. One group, comprising relays 18 and 19 may consist of any 60 number of relays, each relay being individual to some particular marker, while the other group consists of two relays 16 and 17 which are individual to each of the indicating devices. When a marker encounters trouble, a relay of each group is operated 65 and the particular marker is connected over

the common leads 33, directly to one of the indicating devices.

Should a second marker encounter trouble in an attempt to establish a subsequent telephone connection while the first case of trouble is being recorded, the second case will be registered and held in the second, or alternate, indicating device, until the record of the first case is completed. This arrangement will permit the release of the 75 marker as soon as the trouble is registered, and the unnecessary delay caused by the marker being held until its trouble is recorded, is eliminated.

Detailed description of the operation.

In the establishment of telephonic connections as described in Patent No. 1,594,003, issued July 27, 1926, to W. W. Carpenter, the markers may become disabled at any 85 of the various points in their progress from the time they are seized until they have completed the exercise of their control over the associated switches and other apparatus. In order to illustrate the manner in which 90 the trouble indicator control circuit, shown in detail in the drawing, operates, it is assumed that marker 12 encounters trouble at any one of several of its different stages of operation. When the time measuring 95 device in the marker, shown and described in the above mentioned patent to W. W. Carpenter, No. 1,594,003, counts the prescribed interval of time and the marker does not complete its operation in the meantime, 100 battery is connected to the start lead 34 to close an operating circuit for relay 14, the circuit being traceable from ground at relay 22, inner back contact of relay 15, through the upper winding of relay 14, lower 105 contact of relay 24, lead 34, to battery. Relay 14 operates and locks in a circuit extending through its lower winding and front contact, through the winding of relay 15 to ground. Relay 15 operates and opens 110 at its inner back contact, the original operating circuit for relay 14 but relay 14 is maintained operated over its locking circuit. The operation of relay 15 also closes an operating circuit for multi-contact relay 16, 115 the circuit being traceable from ground at the armature and front contact of relay 15, back contact of relay 31, through the winding of relay 16 to battery. Relay 16 operates and prepares trouble indicator 51 for 120 connection to marker 12 so that the trouble therein may be registered.

The operation of relay 16 connects the lowermost conductor of group 33 to ground, thereby closing a circuit extending over conductor 35, outer upper contact of relay 14, through the winding of multi-contact relay 19, to battery. Relay 19 operates and completes the connection of the disabled marker 12 with the indicator 51, which is assumed 125

to be in the preferred position at this time, in view of the operated condition of relay 16, and the registration of the trouble in the marker is therefore displayed by lighted lamps in the indicator 51. The operation of relay 19 connects ground to the conductor next to the lowermost of group 33 to close an obvious operating circuit for relay 21, which operates and locks in a circuit extending through its inner upper contact, conductor 36, to ground at the lower normal contact of relay 28, which locking circuit is also extended over conductor 40, through the windings of the registering relays (not shown) of the indicator 51, to ground, thereby holding the indicator relays operated until the recorder, or printer, has completed the record. The operation of relay 21 also closes an operating circuit for relay 26, and the circuit may be traced from ground at the inner lower contact of relay 21, conductor 37, upper normal contact of relay 27, through the winding of relay 26, to battery. Relay 26 operates and connects the recorder, or printer, 53 to the indicator 51 so that a permanent record may be had of the case of trouble registered in the indicator. This printer is common to both indicators 51 and 52 and should the printer be engaged in recording a case of trouble at a time when a second case of trouble is registered, the second indicator will hold its registration of the second case of trouble until the printer is free to make the record. The operation of relay 21 likewise closes an operating circuit for relay 22, the circuit being traceable from ground at the outer lower contact of relay 21, upper normal contact of relay 30, through the winding of relay 22, to battery. Relay 22 operates and closes an operating circuit for relay 24, the circuit being traceable from ground, front contact of relay 22, conductor 38, inner upper contact of relay 14, make-before-break contact and through the winding of relay 24, conductor 34, to battery in the marker. Relay 24 operates and locks in the circuit extending to ground at its upper armature and opens its own original operating circuit at its make-before-break contact.

The operation of relay 26 connects ground at the lowermost conductor of group 39 to the winding of relay 28 which consequently operates, thereby preventing indicator 52 from being connected to the printer while a record of the registration on indicator 51 is being made. The operation of relay 28 also opens its make-before-break contact and substitutes the ground at relay 32 in the printer circuit and the locking circuit for relay 21 is maintained closed.

When relay 24 operates, as described above, it opens the locking circuit for relay 14 and the latter relay returns to normal, thereby causing the release of relay 15. The release of relay 14 also opens the operating circuit for multi-contact relay 19 which is associated with the marker which encountered the trouble and relay 19 is de-energized thereby permitting the marker to be released and to be available for other calls. The release of relay 15 closed at its outer contact, a circuit extending over the outer upper contact of relay 21, through the lower winding of relay 30, lower contact of relay 29, through the left-hand winding of polarized relay 31, to battery. Relay 30 operates and locks in a circuit extending to ground at the outer lower armature of relay 21. The left-hand winding of polarized relay 31 is designed to attract its armature in the circuit just traced, and the operation of this relay opens the operating circuit for relay 16, causing it to release and disconnect the indicator 51 from the conductor group 39. Furthermore, the operation of relay 31 prepares a circuit which is arranged to connect indicator 52 when the same marker, or another marker, encounters a subsequent case of trouble. The polarized relay is arranged to maintain its armatures in either an attracted or repulsed position, until the current which is passed through the winding thereof changes its direction. This arrangement permits the indicators 51 and 52 to be selected alternately.

The release of the marker removes the battery supply from the locking circuit for relay 24 and the relay returns to normal. The operation of relay 30 opens the operating circuit for relay 22 and the latter relay releases thereby providing ground potential for an operating circuit for another marker which may encounter trouble. The operation of relay 30 also opens the circuit extending through the right-hand winding of relay 31 so that the current passing through the left-hand winding cannot be interfered with while the record of the trouble is being printed.

When the record of the trouble has been printed, relay 32 in the printer's circuit is arranged to operate momentarily to open the locking circuit for relay 21 and the latter relay releases which in turn causes the release of relays 26, 30 and 28 and opens the circuit extending through the left-hand winding of relay 31. Relay 31, however, in becoming deenergized, does not affect the position of its armature, the armature remaining connected to the front contact of the relay.

When a second case of trouble is to be recorded, battery is connected to the start lead, which in this case is assumed to be conductor 41, and relay 13 is operated, causing, as in the first case when relay 14 was operated, the operation of relay 15. Inasmuch as the polarized relay 31 has its armature now closed to its associated front con-

tact, a circuit is closed to operate the multi-contact relay 17 and the indicator 52 associated with relay 17 is connected to the conductors 33. The operation of relay 17 effects the operation of multi-contact relay 18 which is associated with the marker encountering the second case of trouble and the marker is therefore connected to indicator 52 which registers the trouble. The operation of relays 15, 17 and 18 effects the same cycle of operations in their respectively associated relays as was effected in the relays associated with relays 16 and 19 as hereinbefore described.

15 Should the second case of trouble come in before the printer is finished recording the first one, relays 13, 17, 15, 18, 20 and 22 would operate in their regular sequence but inasmuch as relay 28 would still be in an operated condition for the first case of trouble, the operating circuit for relay 25 would be open at the upper back contact of relay 28 and therefore relay 25 could not be operated, thus preventing the connecting of indicator 52 to the printer at this time. The operation of relay 28 has, however, prepared a circuit at its upper front contact, which would now be completed by the operation of relay 20, the circuit extending from ground at the inner lower contact of relay 20, conductor 42, upper front contact of relay 28, conductor 43, to a special alarm signal (not shown) which would now operate to inform the attendant that a case of trouble is registered at indicator 52. The operation of relay 22 would effect the operation of relay 23 and consequently relays 13, 15 and 18 would release. As soon as the record of the first case had been printed, relay 32 would operate momentarily and cause the release of relays 21, 26, 30 and 28. The release of relay 30 would permit the operation of relays 29 and 31 and the release of relay 28 would close the operating circuit for relay 25 which would now operate to permit the recording of the second case of trouble. The operating circuit for relays 29 and 31 could be traced from ground at the outer armature of relay 15, outer upper contact of relay 20, through the lower winding of relay 29, lower back contact of relay 30, through the right-hand winding of relay 31, to battery and relay 31, having its armature in an attracted position at this time, as hereinbefore stated, would repel its armature, inasmuch as a direction of the current is reversed in the relay in passing through the right-hand winding. The armature in its repelled position prepares a circuit at the back contact of the relay for the engagement of indicator 51 for the next case of trouble encountered in a marker. It is therefore seen that the selection of indicators 51 and 52 is alternate.

65 Certain changes in the details of construction herein described will be obvious to those skilled in the art and accordingly, it is not intended to limit the invention except as defined in the appended claims.

What is claimed is:

1. In combination, a plurality of switch controlling mechanisms, a plurality of indicating devices arranged to register the sequence of operations of said mechanisms, a single recorder, means for connecting any one of said switch controlling mechanisms to any of said indicating devices, and means for connecting said recorder to any of said indicating devices for the purpose of producing a permanent record giving information showing the sequence of operations. 70
2. In combination, a plurality of switch controlling mechanisms, a pair of indicating devices arranged to register the progress of said controlling mechanisms, and a single recorder common to said controlling mechanisms and said indicating devices arranged to make a permanent record of the progress of said controlling mechanisms. 75
3. In combination, a plurality of switch controlling mechanisms, a pair of indicating devices arranged to register the progress of said controlling mechanisms, a single recorder adapted to be selected and operated by either of said indicating devices and means for selecting the indicating devices alternately. 80
4. In combination, a plurality of switch controlling mechanisms, a pair of indicating devices arranged to register the progress of said controlling mechanisms, duplex means for selecting the indicating devices in a predetermined order, and a single printer adapted to be automatically selected and operated by either of said indicating devices for the purpose of printing a permanent record of the progress of said mechanisms. 85
5. In combination, a plurality of switch controlling mechanisms for governing a series of operations of switching apparatus, a pair of indicating devices arranged to register the progress of said controlling mechanisms, individual means for connecting said controlling mechanisms with either of said indicating devices, and a single printer for making a permanent record showing which controlling mechanism and indicating device are interconnected, and the progress made by such controlling mechanism. 90
6. In combination, a plurality of switch controlling mechanisms, a pair of indicating devices, adapted to register the progress of said controlling mechanisms and arranged to be selected alternately, means for releasing the controlling mechanisms as soon as the progress thereof is registered in the indicating device, a single printer common to both indicating devices, and means for hold- 95

ing the registration of one device while the printer is engaged in recording the registration of the other device and permitting the registration of the first mentioned device 5 when the registration of the second indicating device is completed.

7. In combination in a telephone system, a plurality of switch controlling mechanisms for governing the operations of the switch- 10 ing apparatus involved in extending connections, a plurality of indicating devices adapted to register the progress of said connections, a plurality of means for connecting any one of said devices to any one of 15 said controlling mechanisms if said mechanisms fail to function properly and means for producing a permanent record giving information of the different degrees of progress made by said mechanisms.

8. In combination in a telephone system, a plurality of markers for governing the operations of switching apparatus involved in extending connections, a pair of indicating devices adapted to register the progress 20 of said connections, duplex means for selecting the indicating devices in a predetermined order and connecting said devices to any one of said markers if such marker fails to function properly, and a single printer for producing a permanent record giving information of the different degrees of progress 25 made by such markers.

9. The combination in a telephone system 30 of a plurality of markers for governing the operations of switching apparatus involved

in extending connections, a pair of indicating devices adapted to register the progress of said connections, means for selecting said indicating devices alternately and connecting said device to any of said markers if 40 such marker fails to function properly, and a single recording device for producing a permanent record giving information of the different degrees of progress made by said markers. 45

10. The combination in a telephone system of a plurality of markers for governing the operations of switching apparatus involved in extending connections, a pair of indicating devices adapted to register the progress 50 of said connections, means for selecting said indicating devices alternately and connecting said device to any one of said markers if such marker becomes disabled and fails to function properly, means in said first 55 mentioned means for releasing the marker when the progress thereof, up to the point where trouble occurred, is registered, a single recorder common to both indicating devices for making a permanent record of 60 the connection in any disabled marker, and other means in the first mentioned means for delaying, if both indicating devices are registering trouble, the recording of one 65 case of trouble until said recorder has completed the record of trouble registered on the indicating device in the preferred position.

In witness whereof, I hereunto subscribe my name this 10th day of April A. D., 1925.

EDWARD E. HINRICHSEN.
